UNITED STATES PATENT OFFICE.

ALFRED FRESCHL, OF CHICAGO, ILLINOIS.

TUFTED UPHOLSTERING.

SPECIFICATION forming part of Letters Patent No. 654,886, dated July 31, 1900.

Application filed June 13, 1898. Serial No. 683,275. (No model.)

To all whom it may concern:

Be it known that I, ALFRED FRESCHL, of Chicago, in the county of Cook and State of Illinois, have invented certain new and useful Improvements in Tufted Upholstering; and I do hereby declare that the following is a full, clear, and exact description thereof, reference being had to the accompanying drawings, and to the letters of reference marked thereon, which form a part of this specification.

This invention relates to an improved construction in tufted or plaited upholstering.

The invention consists in the matters hereinafter described and more particularly pointed out in the appended claims.

In the drawings, Figure 1 is a vertical section of a cushion made in accordance with my invention, said section being taken through the points at which the outer covering is tufted to the backing. Fig. 2 is a similar section taken between said tufting-points. Fig. 3 is a bottom plan view, broken away, showing the construction of the cushion. Fig. 4 is an enlarged detail section taken through one of the tufting-points. Fig. 5 is a bottom plan view of one of the tufting-buttons. Fig. 6 is a side elevation of another form of tufting-button.

In said drawings, A designates the outer flexible covering, and B designates a backing or foundation which is made of the full size of the cushion and made of strawboard, canvas, or the like, as preferred.

C designates the filling material, of curled hair or the like, which is placed between said outer covering and backing and arranged in bunches which occupy the several cells formed between the points at which the covering and backing are attached to each other, and D designates the tufting devices which are inserted through said covering and through the backing or foundation and which hold the two parts of the cushion together at the tufting-points.

E designates a washer which is slipped over the tufting device outside of the backing B and located between an enlarged or folded part of said device and the backing. The

tufting device shown in Figs. 1, 3, and 4 consists of a button D', provided with a plurality of prongs d, which pass through a central

opening in said washer, as shown in Figs. 3 and 4, and are bent or folded at their outer ends to overlie the outer surface of said washer.

F F designate a plurality of retaining-pieces, made of cardboard or like rigid material and made of a shape corresponding to about that of the lower or foundation sides of the cells formed between the tufting-points. One of said retaining-pieces is inserted between the backing B and the filling of each cell. Said washer E is made of such diameter as to extend radially outside of or overlap the proximate corners of said retaining-pieces. As herein shown, the prongs are four in number and are arranged diagonally with respect to the line passing between two adjacent cells. Said prongs are made of such length as to each overlap one corner of an adjacent retaining-piece and may be made sufficiently rigid to hold said retaining-pieces in place without the interposition of the washers. In this event four prongs for each device are employed. I prefer, however, to use the washers, as said washers serve to more securely hold or confine the retaining-pieces at the corners of the same whether the tufting devices have one, two, three, or four prongs.

In Fig. 7 I have shown a fastening consisting of two parts G G', both provided with shanks g g', of which the shank g is made tubular, and the shank g' is adapted to be inserted therein and is constructed so that it will be expanded when the two parts are forced together to hold the said parts from disengagement, the fastener being in this respect like a well-known form of buttons for garments. In connection with a fastener of this character I employ a washer G², said washer being made of sufficient diameter to overlap the proximate corners of the adjacent retaining-pieces, as in the construction heretofore described. The construction of the cushion with respect to the cover, the backing, and retaining-pieces is generally similar to the construction shown in my prior patent, No. 537,385, dated April 9, 1895, with the exception of the means for fastening the parts together, which latter feature constitutes my present invention.

In making a cushion embodying my invention I first place the fabric or flexible mate-

rial constituting the outer covering A over a cellular mold—such, for instance, as shown in my said prior patent, No. 537,385. Said cover is arranged within the cells of said mold by depressing the same therein, the parts of the cover being depressed and successfully held within the cells either by the hand of the operator or by the use of a block, such as is illustrated in my said prior patent, No. 537,385, as found most convenient. After the covering has been thus depressed into each cell of the mold a suitable quantity of stuffing or filling material is inserted into each cell and is held or confined therein by means of the retaining-pieces F. After all the cells have been filled in the manner described and the retaining-pieces placed thereover the backing or foundation B is then placed over the several filled compartments in contact with the retaining-pieces F, and the covering is then secured to the backing and to the corners of the retaining-pieces at the tufting-points or intersection of the cells. As an additional means of securing the parts together the backing may be pasted to the retaining-pieces and also the cover at the tufting-points. The tufting devices may be held in place to be inserted through the fabric forming the outer covering and the backing of the cushion in the manner shown in my prior patent, Reissue No. 11,779, or in any other suitable manner. In my said prior patent, No. 537,385, is shown and described a tufted upholstering provided with retaining-pieces wherein the backing is secured to said pieces and to the covering by glue or cement. By the employment of fastening means, such as are here described, adapted to be secured to the corners of the retaining-pieces as well as the backing and the covering at the tufting-points I produce a construction which is much stronger and more durable than that described in said prior patent. The construction wherein the washers overlap said retaining-pieces serve to form, in effect, a full double backing and to provide a backing made as strong as if two full layers were employed.

I claim as my invention—

1. As a novel article of manufacture, a tufted cushion which embraces a covering of flexible material, filling material, separate retaining-pieces of cardboard or the like, ap-

plied to hold the filling material between the tufting-points, a backing-piece, and fasteners at the tufting-points which pass through the covering and backing-piece, and are provided with a part outside of the backing-piece which overlaps the corners of the adjacent retaining-pieces.

2. As a novel article of manufacture, a tufted cushion which embraces a covering of flexible material, filling material, separate retaining-pieces of cardboard or the like applied to hold the filling material between the tufting-points, a backing-piece and fasteners which pass through the cover and backing-piece, said fasteners each having at one end a head or button, and washers applied to the outer surface of the backing-piece and which overlap the corners of the adjacent retaining-pieces, the parts of said fasteners outside of the washer being spread to engage the outer surface of said washers.

3. As a novel article of manufacture, a tufted cushion which embraces a covering of flexible material, filling material, separate pieces of cardboard applied to hold the filling material between the tufting-points, a backing-piece and fasteners which engage the covering and backing-pieces, said fasteners consisting of buttons provided with prongs and washers interposed between the prongs and the backing-layer and adapted to overlap the corners of the retaining-pieces.

4. As a novel article of manufacture, a tufted cushion which embraces a covering of flexible material, filling material, separate retaining-pieces applied to hold the filling material between the tufting-points, a backing-piece and fasteners which engage the covering and backing at the tufting-points, said fasteners consisting of buttons provided with four prongs which are bent outwardly in position to overlap the adjacent corners of said filling-pieces.

In testimony that I claim the foregoing as my invention I affix my signature, in presence of two witnesses, this 10th day of June, A. D. 1898.

ALFRED FRESCHL.
